UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 2, 1924. Serial No. 703,670.

My invention relates to electric furnaces and particularly to means for and methods of supporting electric resistor units in electric furnaces.

One object of my invention is to provide a relatively simple and practical means for supporting an electric resistor unit in an electric furnace.

Another object is to provide an electric resistor unit constructed to be removable from, and supported by, the walls of an electric furnace and gravitationally locked thereto.

Other objects will appear from the description of the invention.

In practicing my invention, I provide an electric resistance element of any well known structure supported by a plurality of refractory members to comprise an electric resistor unit. The resistor unit is supported by the wall of an electric furnace of any well known structure by means of resistor unit supporting members in such manner that the resistor unit supporting members are gravitationally locked to said walls and removable therefrom. By means of this structure, I provide a simple and practical means for supporting an electric resistor unit that may be readily installed and removed to permit repairs to be made.

In the single sheet of drawings,

Figure 1 is a vertical elevational view, partially in lateral section, of a structure embodying my invention;

Fig. 2 is a side elevational view of a refractory resistor unit supporting member employed in my invention;

Fig. 3 is a top plan view of the unit shown in Fig. 2;

Fig. 4 is a front elevational view, partly in section and partly broken away, of another embodiment of my invention, and

Fig. 5 is a side elevational view of another embodiment of a refractory resistor unit supporting member that may be employed in my invention.

A plurality of refractory furnace walls 11 enclose a furnace chamber 12. An electric resistance element 13 comprises a plurality of return-bent convolutions maintained in spaced relation by a plurality of vertically extending grooved refractory members 14. A plurality of refractory members 15 are

supported by the walls of the furnace and support the refractory resistance-element-supporting members 14, said members with the electric resistance element comprising a resistor unit that is mounted on the refractory resistor unit supporting members 15 in a manner which is hereinafter more fully described.

The resistor supporting members 15 comprise an inner portion 16 of substantially arcuate shape, interfitting with a chamber 17 in the furnace wall, and an outer portion 18 of substantially T-shape that extends into the furnace chamber. The portion of arcuate form is so shaped and located relatively to the face of the furnace wall that the center of curvature is above the member in a vertical plane located within the furnace wall. By so locating the center of curvature, the member can be removed only by an upwardly and outwardly directed force and is consequently locked in operative position by gravitational force. The radius of curvature may vary from the smallest practical dimension to an infinite length in which event, the inner portion is located angularly and downwardly relatively to the outer portion. The T-shaped portion 18 of the resistor unit supporting members are perforated at 19 to provide for the insertion of refractory pin members 21 that have portions extending beyond both the upper and lower surfaces of said resistor unit supporting members to retain the members 14 in position.

In Fig. 5, I have shown another embodiment of a resistor unit supporting member 22, the interfitting portion of which comprises substantially a segment of a sphere and the portions extending into the furnace chamber being of substantially straight elongated form. Other shapes may be utilized without departing from the spirit of my invention.

In Fig. 4, the resistor unit supporting member 15 directly supports a resistance element comprising a plurality of convolutions of substantially ribbon shape. Other methods of mounting the resistance element upon the resistor unit supporting member may be used without departing from the spirit of my invention.

The resistor unit supporting members 15,

when mounted upon the walls of the furnace as hereinbefore described are gravitationally locked thereto and are removable in an arcuate path laterally therefrom.

5. In mounting the resistor unit, the resistance element 13 may be assembled with the grooved refractory members 14 and placed in operative position with respect to the unit supporting members 15 by a lateral
- 10 movement relatively thereto. The refractory pin shaped members 21 may be inserted into the perforations 19 to lock the refractory members 14 in operating position, thereby preventing any lateral movement of said
- 15 members that may tend to occur by reason of the expansion and contraction of the resistance element 13 through the alternate heating and cooling incidental to the operation of the furnace.
- 20 It is obvious that my invention provides a relatively simple and practical structure. The resistor unit is readily mounted, and, in case of burn-outs or other incidents in the operation of the furnace necessitating re-
- 25 placement of resistor units, my invention provides simple means for permitting the removal of the used unit and the insertion of a new unit.

Various modifications may be made in the device embodying my invention without departing from the spirit and scope thereof, and I desire that only such limitations shall be placed thereon as are imposed by the prior art or are specifically set forth in the appended claims.

I claim as my invention:

1. In an electric furnace, the combination with a wall having an opening therein, of a resistor-unit-supporting member having a portion projecting loosely into said opening, supported by said wall and removable laterally therefrom by an upward arcuate movement.
- 40 2. In an electric furnace, the combination with a wall, of a plurality of resistor-supporting members extending into and supported by said wall, removable laterally therefrom in an upwardly arcuate path and gravitationally locked thereto.
- 45 3. In an electric furnace, the combination with a plurality of refractory walls enclosing a furnace chamber and a resistor unit having a plurality of vertically-extending refractory members, of a plurality of refractory resistor-unit-supporting members gravitationally locked to said walls, and means engaging said supporting members for preventing lateral movement of said vertically-extending refractory members with respect thereto.
- 50 4. In an electric furnace, the combination with a plurality of refractory walls enclosing a furnace chamber and a resistor unit having a plurality of vertically-extending refractory members, of a plurality of refrac-

tory resistor-unit-supporting members removable laterally from said walls and having means for preventing lateral movement of said vertically-extending refractory members with respect thereto.

5. In an electric furnace, the combination with a plurality of refractory walls enclosing a furnace chamber and a resistor unit having a plurality of vertically-extending refractory members, of a plurality of refractory resistor-unit-supporting members gravitationally locked to and removable laterally from said walls, and having means for preventing lateral movement of said vertically-extending refractory members with respect thereto.

6. In an electric furnace, the combination with a wall for a furnace chamber, of a refractory resistor-unit-supporting member engaged by said wall in supporting relation, the wall-engaging end of said member being of substantially arcuate shape.

7. In an electric furnace, the combination with a plurality of refractory walls enclosing a furnace chamber, of a plurality of refractory resistor-unit-supporting members engaged by said walls in supporting relation, the wall engaging portions of said members being of substantially arcuate shape and removable from their normal operating position relatively to said walls in a substantially arcuate path.

8. In an electric furnace, the combination with a plurality of refractory walls enclosing a furnace chamber, of a plurality of refractory resistor-unit-supporting members having a portion of substantially arcuate shape engaging said walls in supporting relation and another portion of substantially T shape extending into the furnace chamber, said members being removable from their normal operating position relatively to said walls in a substantially arcuate path.

9. In an electric furnace, the combination with a wall for a furnace chamber, of a refractory resistor-unit-supporting member extending into and supported by said wall and removable laterally and upwardly in an arcuate path therefrom.

10. In an electric furnace, the combination with a plurality of refractory walls enclosing a furnace chamber, of a plurality of refractory resistor-unit-supporting members engaged by said walls in supporting relation, the wall engaging portions of said members being of substantially arcuate shape and removable from their normal operative position relatively to said walls in a substantially upwardly extending arcuate path.

11. In an electric furnace, the combination with a plurality of refractory walls enclosing a furnace chamber, of a heating-unit-supporting member engaged by one of said walls in supporting relation, an outer portion of said member being located in the

chamber and an inner portion located in the wall and extending angularly downwardly relatively to said outer portion.

12. In an electric furnace, in combination, a refractory wall having an opening therein, and a resistor-supporting member having a portion fitting loosely into said opening, the weight of a resistor supported thereby tending to lock the supporting member in proper operative position in said opening.

13. In an electric furnace, in combination,

a refractory wall having an opening therein and a resistor-supporting member having a portion fitting loosely into said opening to support the member, the member being removable from said wall by a movement longitudinally thereof in other than a straight line motion.

In testimony whereof, I have hereunto subscribed my name this 24th day of March, 1924.

ALVIN D. KEENE.
